[57] **CLAIM**

The ornamental design for electronic flash unit, as shown.

DESCRIPTION

FIG. 1 is a front elevational view of an electronic flash unit showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear perspective view thereof; and

FIG. 8 is a front perspective view thereof.

FIG. 1.

FIG. 2.

FIG. 3.

FIG. 4.

FIG. 5.

FIG. 6.

FIG. 7.

FIG. 8.
